UNITED STATES PATENT OFFICE.

ARNO HAHN, OF BOULDER, MONTANA.

WATER-CIRCULATOR.

1,399,617.

Specification of Letters Patent. Patented Dec. 6. 1921

Application filed June 1, 1920. Serial No. 385,860.

To all whom it may concern:

Be it known that I, ARNO HAHN, a citizen of the United States, residing at Boulder, in the county of Jefferson and State of Montana, have invented new and useful Improvements in Water-Circulators, of which the following is a specification.

This invention relates to the cooling system of motor operated vehicles, and comprehends a device which can be readily and easily installed on any make of car, the device being operable to assist in circulating the water on its prescribed course, maintaining the motor at a more uniform and low temperature, thus preventing the engine from overheating which materially reduces the efficiency of a motor.

More specifically stated, the invention makes use of a propeller operated from the fan belt of the motor, the propeller being disposed in the connection between the radiator and the water jacket of the motor, the propeller operating to increase the flow or circulation of the water for the purposes above mentioned.

The nature and advantages of the invention will be better understood when the following detailed description is read in connection with the accompanying drawing, the invention residing in the construction, combination and arrangement of parts as claimed.

In the drawings forming part of this application like numerals of reference indicate similar parts in the several views, and wherein:

Figure 1 is a fragmentary view of the forward end of a motor vehicle, showing the relative position of the invention with respect to the radiator, water-jacket of the motor and the fan belt.

Fig. 2 is an enlarged sectional view taken through the combined water and propelling casing and the bearing for the propeller shaft.

Fig. 3 is a sectional view taken on line 3-3 of Fig. 2.

Fig. 4 is a fragmentary view showing the arrangement of the pulley with respect to the fan belt for rotating the propeller shaft in a reverse direction from that shown in Figs. 1 and 2.

Fig. 5 is a detailed view of the propeller.

Referring to the drawings in detail A indicates a portion of the radiator of a motor

vehicle, B the fan belt, and C the water inlet to the water-jacket of the engine.

The device forming the subject matter of my invention comprises a combined water and propeller casing indicated at D, and made up of two sections 10 and 11 respectively, each of which has an annular flange arranged in face to face contact and secured together by means of fastening elements 12. This casing is arranged between the water outlet opening of the radiator, and the water inlet opening of the water-jacket, providing a connection between these parts, to which the casing D is secured by means of short lengths of hose 13 and hose clamps 14 of usual construction. The section 10 of the casing D is formed with an offset portion 15 having a bore 16 opening at one end into the casing D, and at its upper end above the casing, the bore being internally threaded for a portion of its length as at 17. Threaded into this bore is a sleeve like member 18 constituting a bearing for the shaft 19, the shaft passing through a packing gland 20 secured to one end of the sleeve as shown. The sleeve is provided with an aperture through which oil or other suitable lubricant may be introduced, the opening being normally closed by a plug 21. The sleeve 18 projects a slight distance within the casing D, while the shaft 19 passed through the sleeve projects within the casing and supports a propeller 22 of any suitable construction. The opposite end of the shaft 19 supports a cone shaped pulley 24 which is arranged at one side of the fan belt B and engaged by the latter, so that when the motor is in operation, rotation is imparted to the shaft 19 through the instrumentality of the fan belt. In Figs. 1 and 2, the pulley 24 is shown arranged at that side of the fan belt, so that the shaft 19 is rotated toward the left, and if found necessary to rotate the shaft in the opposite direction, the pulley 24 can be arranged at opposite side of the belt as illustrated in Fig. 4.

In practice, the casing D is arranged between the outlet end of the radiator and the inlet end of the water-jacket of the motor, and held in position by the clamps and hose connection as shown. When the motor is in operation, the pulley 24 contacting the fan belt B, causes the shaft 19 to rotate, and as the propeller 22 is arranged within the water casing D, it forces the water through

the casing from the radiator to the inlet opening of the water-jacket. The propeller operates to materially assist the circulation of water through the entire cooling system, 5 and by reason of the fact that the water casing and the propeller casing are combined, there is provided sufficient by-pass for the water to flow by the thermo-siphon action, should the propeller at any time fail to work.

10 The invention is particularly advantageous in maintaining a more uniform and low temperature of the motor, thus preventing overheating of the motor and boiling over of the radiator. The rapidity with which the propeller is actuated, may be controlled by setting the pulley 24 so that the fan belt B will contact more or less of its circumference.

15

While it is believed that from the foregoing description, the nature and advantages 20 of the invention will be better understood, I desire to have it understood that I do not

limit myself to what is herein shown and described, and that such changes may be resorted to when desired as fall within the scope of what is claimed.

What I claim is:

The combination with a water cooled engine of a motor vehicle, of a substantially tubular member interposed between the outlet of the radiator and the inlet of the water jacket, an obliquely disposed portion of said member constituting a bearing, a shaft journaled in said bearing and projecting from said member in the direction of the fan belt 30 pulley, a cone-shaped pulley carried by the free end of said shaft and arranged to be driven by the fan belt, and a propeller carried by the opposite end of the shaft and operating in said tubular member for the purpose specified.

In testimony whereof I affix my signature.

ARNO HAHN.
